SHEET DELIVERY MECHANISM FOR
PRINTING PRESSES

Howard M. Barber, Pawcatuck, Conn., assignor to
C. B. Cottrell & Sons Company, Westerly, R. I.,
a corporation of Delaware

Application March 3, 1934, Serial No. 713,807

13 Claims. (Cl. 271—79)

I have discovered that sheets can be delivered from a rotary printing press at a higher speed by the use of side grippers rather than front grippers but that front grippers are more efficient in taking the sheets from the rotary sheet carrier, as, for instance, the impression cylinder. Therefore, the object of my invention, generally, is to provide a sheet delivery comprising coacting front and side grippers, the front grippers being caused to take the sheets from the rotary sheet carrier and thereafter release the sheets to the side grippers and the side grippers being caused to take the sheets from the front grippers and thereafter release the sheets at the delivery point.

The object of my invention, more particularly, is to provide a sheet delivery of the above character in which the side grippers are adjustable, for handling sheets of different widths.

20 My invention, more particularly, comprises an endless delivery carrier having side chains for mounting the front and oppositely disposed side grippers in sets along the same, the said sets of front and side grippers being properly positioned 25 along the endless carrier, for taking the sheets from the rotary sheet carrier and the oppositely disposed side grippers of each set being adjustable toward and away from each other, for handling sheets of different widths.

30 A practical embodiment of my invention is represented in the accompanying drawings, in which Fig. 1 represents in end elevation so much of a rotary printing press as includes my improved sheet delivery;

35 Fig. 2 represents a section taken in the plane of the line II—II of Fig. 1, looking in the direction of the arrows; three sets of front and side grippers being shown on the endless delivery carrier;

40 Fig. 2a represents a detail section showing the means for feeding sheets to the impression cylinder;

45 Fig. 3 represents a transverse section, on an enlarged scale, showing one of the side chains of the endless carrier and the parts adjacent thereto;

Fig. 4 represents a section taken in the plane of the line IV—IV of Fig. 3, looking in the direction of the arrows;

50 Fig. 5 represents a section taken in the plane of the line V—V of Fig. 3, looking in the direction of the arrows;

55 Fig. 6 represents a section taken in the plane of the line VI—VI of Fig. 3, looking in the direction of the arrows;

Fig. 7 represents a section taken in the plane of the line VII—VII of Fig. 6, looking in the direction of the arrows; and

Fig. 8 represents a section taken in the plane of the line VIII—VIII of Fig. 6, looking in the direction of the arrows.

The impression cylinder 1 which acts as a rotary sheet carrier is provided in the present instance with two diametrically opposed head grippers 2 operated by a suitable cam 4 to take 10 the sheets at one point from a sheet feeding cylinder 3 and to release the sheets at another point to my improved sheet delivery.

This sheet delivery is shown as comprising an endless carrier having two horizontally disposed 15 side chains 5 traveling in parallel endless paths around the usual sprocket wheels 6.

Front and side grippers are carried by the side chains 5 of the endless delivery carrier, said grippers being arranged in sets comprising two 20 oppositely disposed side grippers and their coacting front gripper. Each set of these front and side grippers is constructed, arranged and operated as follows:

A fixed crossbar 7 and a rocking crossbar 8 are mounted at their ends in divided brackets carried 25 by the side chains 5. Each divided bracket comprises an upper member 9 and a lower member 10. Two pins 12 are clamped at their inner ends between the upper and lower members 9 and 10 of the divided clamp by a suitable screw bolt 11, 30 which pins 12 project through the pivot holes of one of the links of the side chain 5 and are there fastened by removable cotter pins 13.

The front grippers of a set comprise stationary jaws 14 fast on the fixed crossbar 7 and coacting 35 movable jaws 15 fast on the rocking crossbar 8.

Each of the pair of oppositely disposed side grippers of a set comprises coacting stationary and movable jaws 16 and 17 carried by a divided collar comprising two half members 18 and 19 40 clamped together around the fixed crossbar 7 by suitable screw bolts 20. The fixed jaw 16 forms an integral part of the half member 18 of the divided collar and it is provided with a stud 21 on which the hub 22 of the movable jaw 17 45 is pivoted. This hub 22 is also provided with a toothed segment 23 and a spring engaged arm 24. An overthrow spring 25 is located between the outer end of the arm 24 and the outer end of an arm 26 projecting from the stationary jaw 16. This spring 25 is so arranged that it will 50 yieldingly hold the movable jaw 17 in either of its open or closed positions.

A stud 27 projecting from the half member 18 of the divided collar serves as a pivot for the hub 55

28 of a rock lever, one arm 29 of which carries a cam controlled stud or roller 30 and the other arm 31 of which carries a toothed segment 32 meshing with the toothed segment 23 of the movable jaw 17. A lug 33 serves as a stop for limiting the opening movement of the movable jaw 17.

The means for controlling the operation of the front grippers of a set is as follows:

10 A cam 34 is located in position to engage a stud or roller 35 carried by an arm 36 fast on the rocking bar 8 to cause the jaws 14, 15 of the front grippers to take a sheet from the grippers 2 of the impression cylinder 1 as each set of front and side grippers on the endless delivery carrier reach the proper point of transfer from the impression cylinder. Another cam 37 is located in position to cause the front grippers to release the leading ends of the sheets after the sheets have been taken by the jaws 16, 17 of the 20 opposed side grippers of the set.

The means for controlling the operation of the side grippers of the set is as follows:

25 Two cams 38 are located in position to cause the opposed side grippers of a set to take the sheets from the front grippers of their set and to release the sheets as they reach the delivery point, i. e., a position over the delivery pile 39. These cams 38 are adjustably secured along the frame crossbars 40 as by set screws 41.

30 The opposed side grippers of each set may be adjusted laterally of the endless delivery carrier toward and away from each other, for handling sheets of different widths. This is done by moving the stationary and movable jaws 14 and 35 15 of the front grippers along their fixed and rocking bars 7 and 8 respectively, the gripper jaws being secured in their adjusted positions as by the set screws 42 and 43 respectively.

35 It will be understood that the cams 38 on the crossbars 40 must be adjusted laterally of the endless carrier along the crossbars, to bring them into their operative position with respect to their respective side grippers.

In operation: The front grippers of each set 45 are operated at the proper point to take a sheet from its grippers on the rotary sheet carrier. As the sheet travels toward its delivery point the front grippers are released from the sheet after the side grippers of the set have grasped the sheet. These side grippers in turn are then operated to release the sheet as it reaches its delivery point.

40 From the above description it will be seen that I have provided simple and efficient means for 55 delivering sheets rapidly from a rotary sheet carrier, such, for instance, as the impression cylinder of a rotary sheet feed printing press, said delivery means including coacting front and side grippers.

60 It is evident that various changes may be resorted to in the construction, form and arrangement of the several parts without departing from the spirit and scope of my invention, and hence I do not intend to be limited to the particular 65 embodiment herein shown and described, but

What I claim is:

1. A rotary sheet carrier and an endless sheet delivery therefor comprising front and side grippers, means for causing the front grippers to take the sheets from the rotary sheet carrier, means for causing the front grippers to release the sheets to the side grippers, and means for causing the side grippers to take the sheets from their front grippers and release the sheets at the delivery point.

2. A rotary sheet carrier and an endless sheet delivery therefor comprising front and side grippers arranged in sets, means for causing the front grippers of a set to take the sheets from the rotary sheet carrier, means for causing the front grippers to release the sheets to the side grippers of the set, and means for causing the said side grippers to take the sheets from their front grippers and release the sheets at the delivery point.

3. A rotary sheet carrier and an endless sheet delivery therefor comprising front and side grippers, means for causing the front grippers to take the sheets from the rotary sheet carrier, means for causing the front grippers to release the sheets to the side grippers, and means for causing the side grippers to take the sheets from their front grippers and release the sheets at the delivery point, the side grippers being adjustable laterally, for handling sheets of different widths.

4. A rotary sheet carrier and an endless sheet delivery therefor comprising front and side grippers arranged in sets, means for causing the front grippers of a set to take the sheets from the rotary sheet carrier, means for causing the front grippers to release the sheets to the side grippers of the set, and means for causing the said side grippers to take the sheets from their front grippers and release the sheets at the delivery point, the side grippers being adjustable laterally, for handling sheets of different widths.

5. A rotary sheet carrier and a sheet delivery therefor comprising an endless carrier, front and side grippers mounted thereon, means for causing the front grippers to take the sheets from the rotary sheet carrier, means for causing the front grippers to release the sheets to the side grippers, and means for causing the side grippers to take the sheets from their front grippers and release the sheets at the delivery point.

6. A rotary sheet carrier and a sheet delivery therefor comprising an endless carrier, front and side grippers mounted thereon in sets, means for causing the front grippers of a set to take the sheets from the rotary sheet carrier, means for causing the front grippers to release the sheets to the side grippers of the set, and means for causing the said side grippers to take the sheets from their front grippers and release the sheets at the delivery point.

7. A rotary sheet carrier and a sheet delivery therefor comprising an endless carrier, front and side grippers mounted thereon, means for causing the front grippers to take the sheets from the rotary sheet carrier, means for causing the front grippers to release the sheets to the side grippers, and means for causing the side grippers to take the sheets from their front grippers and release the sheets at the delivery point, the side grippers being adjustable laterally of the endless carrier, for handling sheets of different widths.

8. A rotary sheet carrier and a sheet delivery therefor comprising an endless carrier, front and side grippers mounted thereon in sets, means for causing the front grippers of a set to take the sheets from the rotary sheet carrier, means for causing the front grippers to release the sheets to the side grippers of the set, and means for causing the said side grippers to take the sheets from their front grippers and release the sheets at the delivery point, the side grippers being adjustable laterally of the endless carrier, for handling sheets of different widths.

9. A rotary sheet carrier and a sheet delivery therefor comprising an endless carrier, front and

5 side grippers mounted thereon, two cams, one for causing the front grippers to take the sheets from the rotary carrier and the other for causing the front grippers to release the sheets to the side grippers, and a third cam for causing the side grippers to take the sheets from the front grippers and release the sheets at the delivery point.

10. A rotary sheet carrier and a sheet delivery therefor comprising an endless carrier, front and side grippers mounted thereon, two cams, one for causing the front grippers to take the sheets from the rotary carrier and the other for causing the front grippers to release the sheets to the side grippers, and a third cam for causing the side grippers to take the sheets from the front grippers and release the sheets at the delivery point, the side grippers and their operating cams being adjustable laterally of the endless carrier, for handling sheets of different widths.

15 11. An endless sheet delivery carrier comprising side chains, fixed and rocking crossbars carried by said side chains, front grippers having their fixed and movable jaws mounted on the fixed and rocking crossbars respectively, oppositely disposed side grippers carried by said fixed crossbar, means for adjusting the side grippers toward and away from each other along the fixed crossbar, to handle sheets of different widths, and

20 laterally adjustable cams for controlling the operation of the side grippers.

12. An endless sheet delivery carrier comprising side chains, fixed and rocking crossbars carried by said side chains, front grippers having their fixed and movable jaws mounted on the fixed and rocking crossbars respectively, oppositely disposed side grippers carried by said fixed crossbar, means for adjusting the side grippers toward and away from each other along the fixed crossbar, to handle sheets of different widths, a frame crossbar and cams adjustable along said frame crossbar, for controlling the operation of the side grippers.

15 13. An endless sheet delivery carrier comprising side chains, fixed and rocking crossbars, mounting brackets therefor secured to said side chains, front grippers having their fixed and movable jaws mounted on the fixed and rocking crossbars respectively, oppositely disposed side grippers carried by said fixed crossbar, means for adjusting the side grippers toward and away from each other along the fixed crossbar, to handle sheets of different widths, and laterally adjustable cams for controlling the operation of the side grippers.

20 25 HOWARD M. BARBER.
